(57) CLAIM

The ornamental design for a footwear insole, as shown and described.

DESCRIPTION

FIG. 1 is a rear, bottom perspective view of an example embodiment of a footwear insole showing our new design.

FIG. 2 is a bottom view thereof.

FIG. 3 is a top view thereof.

FIG. 4 is a left side view thereof.

FIG. 5 is a right side view thereof.

FIG. 6 is a front view thereof; and,

FIG. 7 is a rear view thereof.

The Figures of the above example embodiments show a right-footed design; however, it is understood that a left-footed design of the example embodiments would include mirror images of the above Figures.

The broken line showing of the Figures is for purposes of illustration and forms no part of the claimed design.
